UNITED STATES PATENT OFFICE.

CARL P. MILLER, OF FARGO, NORTH DAKOTA.

ROAD-GRADER.

1,354,264.

Specification of Letters Patent. Patented Sept. 28, 1920.

Application filed August 13, 1919. Serial No. 317,368.

To all whom it may concern:

Be it known that I, CARL P. MILLER, a citizen of the United States, residing at Fargo, in the county of Cass and State of North Dakota, have invented certain new and useful Improvements in Road-Graders, of which the following is a specification.

This invention relates to an improved road grader and has as one of its principal objects 10 to provide a device of this character employing companion scraper blades and wherein the blades may be adjusted with respect to each other either for throwing earth toward the center of a road or away from the road 15 center.

The invention has as a further object to provide a grader wherein the blades may be simultaneously elevated without affecting their angular relation with respect to each 20 other and wherein the blades may be simultaneously lowered and pressure brought to bear thereon.

A still further object of the invention is to provide a grader wherein the blades may be simultaneously tilted in a vertical plane 25 so that corresponding ends of the blades may be either raised or lowered.

And the invention has as a still further object to provide a grader which will be substantial and durable and which may be operated with facility.

Other and incidental objects will appear hereinafter.

In the drawings:

Figure 1 is a longitudinal sectional view 35 taken centrally through the grader,

Fig. 2 is a plan view of the device,

Fig. 3 is a transverse section taken on the 40 line 3—3 of Fig. 2 and looking in the direction of the arrows,

Fig. 4 is a detail perspective view showing the mounting of the blades,

Fig. 5 is a vertical sectional view taken 45 on the line 5—5 of Fig. 2 and looking in the direction of the arrows, and

Fig. 6 is a fragmentary plan view showing the locking mechanism employed in connection with one of the blade shifting shafts of the device.

Referring now more particularly to the drawings, I employ a front axle 10 and a rear axle 11 and mounted upon these axles are suitable supporting wheels. The front axle 10 carries a yoke 12 while the rear axle carries a yoke 13 which stands somewhat 50 higher than the front yoke. Upon the front

yoke is mounted an inverted yoke or bolster 14, the arms of which are provided at their upper ends with laterally and outwardly directed lugs to which is secured a cross bar 15. Extending through this bar, the yoke 14, 60 and the yoke 12, is a king bolt 16, the front wheels, of course, being thus adapted to swing about the axis of this bolt. Connected at its rear end to the said bolt is a plate 17 which rests upon the bar 15 and also connected to the bolt is a plate 18 which rests upon the bight of the yoke 14. The plate 17 is bent to extend toward the plate 18 and their forward portions extend in parallel relation to constitute a clevis for receiving a 70 tongue or for connecting the grader with a tractor. Connecting the front portions of the plates is a bolt 19 which is also engaged through braces 20 extending between the bolt and the end portions of the yoke 12. 75

Extending between the yoke 13 and the bolster 14 are spaced horizontal frame bars or sills 21 lying in parallel relation and bolted at their forward ends to the bar 15 while at their rear ends said sills are secured 80 directly to the yoke 13. Upstanding from these sills adjacent the rear ends thereof are spaced parallel posts 22 and secured beneath the posts to the lower sides of the sills 21 is a cross bar 23. A similar cross bar 24 extends 85 between the posts adjacent their upper ends, this cross bar being removably held in position by suitable cotter pins. Slidable vertically upon the posts is a transverse elevating bar 25. As particularly illustrated in 90 Fig. 1, this elevating bar is constructed of reversely presented angle plates lying at opposite sides of the posts and disposed between the plates are spacing strips 26 through which are engaged fastening devices securing the strips and plates together. At their ends, the strips 26 closely confront the inner vertical edges of the posts for thus holding the bar against longitudinal movement with respect to the posts. Fixed between the angle plates of the bar adjacent the outer ends thereof are, as particularly shown in Fig. 3, blocks 27 and threaded through these blocks are vertical screw shafts 28 swiveled 95 at their lower ends upon the ends of the cross bar 23 while the upper ends of said shafts are freely received through the ends of the cross bar 24. The cross bars will thus effectively support said shafts which are provided at their upper ends with hand 100 wheels 29.

105 110

Engaged with the arms of the bolster 14 are loops 30 and freely connected with these loops are arms or rods 31 extending rearwardly and provided at their free ends with laterally and downwardly directed terminal portions. These arms carry companion scraper blades 32 to the lower longitudinal edges of which are secured blade plates 33. Mounted upon the rear sides of the blades 10 at points substantially midway between the ends thereof are, as particularly shown in Fig. 4, bearings 34 through which the lateral terminal portions of the arms 31 are freely received, cotter pins or other appropriate fastening devices engaged through the ends of the arms, detachably securing the blades in position thereon. In this connection it should be observed that the connection between the arms and the blades 15 is such that the blades may be turned each about a vertical axis and may also be rocked longitudinally in a vertical plane. The bearings are provided with apertured lugs projecting at the rear thereof and engaging said lugs are rods 35 pivotally secured at their upper ends to the ends of the elevating bar 25. These rods thus provide an operative connection between the elevating bar 20 and the blades. Extending rearwardly from the blades are brace rods 36 which are, as also shown in Fig. 4, pivotally connected at their front ends with the bearings 34 while, at their rear ends, the rods are freely engaged with loops 37 on the side 25 portions of the yoke 13. As will be clear in view of the preceding description, the hand wheels 29 may be operated for elevating the blades. Similarly, the blades may be lowered into engagement with the 30 ground and pressure brought to bear thereon for causing the blades to bite into the ground. Mounted upon the sills 21 in the rear of the posts 22 is a cross bar 38 upon which is swiveled a seat 39. Thus, an operator riding on this seat may easily manipulate both of the hand wheels.

Freely mounted at its forward end upon the king bolt 16 is a center beam 40 which is preferably constructed from a metallic 35 bar looped around the bolt and having its side portions extending in parallel relation. Fixed between the side portions of the beam adjacent the rear end thereof is a spacer block 41 and threaded through this block is an elevating shaft 42 for the beam. As particularly shown in Fig. 1, the upper end portion of the shaft is freely received through the yoke 13 as well as through a spacing sleeve 43 resting upon said yoke 40 and fixed upon the upper end of the shaft is a hand wheel 44. Extending transversely through the beam adjacent its rear end is a horizontal shaft 45 to one end of which is connected a hand wheel 46 and mounted 50 upon the shaft between the side portions of

the beam is a pulley 47. A smaller pulley 48 is mounted between the side portions of the beam adjacent the forward end thereof and trained over these pulleys is a chain or other approved flexible element 49. Slidable longitudinally upon the beam is a sleeve or carrier 50 through which is engaged an eye bolt 51 received between the side portions of the beam. At its lower end this bolt freely carries a ring 52 which, in turn, is freely engaged through ears 53 secured to the inner ends of the scraper blades at their upper margins and projecting forwardly thereover. The ring 52 will thus connect the blades at their inner ends as 55 well as also connect the blades with the carrier 50. Freely fitted upon the lower end of the bolt 51 beneath the carrier are plates 54 to which are respectively connected the ends of the chain 49. Thus, it will be clear 60 that the hand wheel 46 may be operated for shifting the carrier 50 along the beam 40 and simultaneously adjusting the angular position of the blades. In the drawings, I have shown the blades adjusted to incline 65 inwardly and rearwardly for throwing the earth toward the center of a roadway, the carrier 50 being positioned in a plane behind the plane of the pivotal centers of the blades. However, as will at once be appreciated, by shifting the carrier 50 forwardly along the beam 40 to a position in front of the plane of the pivotal centers of the blades, the inclination of the blades may be reversed when the blades will incline outwardly and rearwardly for throwing the earth from the center of the roadway to the sides thereof. Any intermediate position of adjustment of the blades may also, of course, be had. For locking the blades in 70 adjusted position I provide a ratchet wheel 55 having reversely formed ratchet teeth and mounted to coact with each series of teeth is a pawl 56, one pawl being adapted to lock the shaft against rotation in one 75 direction while the other pawl is adapted to lock the shaft against rotation in the opposite direction.

Extending rearwardly from the rear axle 11 is a substantially U-shaped frame 57 supported by braces 58 extending between the frame and the side portions of the yoke 13. Mounted upon the frame is a platform 59. This platform is provided so that an operator may stand thereon and manipulate the 80 hand wheel 44. By rotating this wheel in one direction, the rear end of the center beam 40 will be raised to in turn elevate the inner ends of the scraper blades. Thus, the blades may be tilted longitudinally in a 85 vertical plane for causing the outer end portions of the blades to bite into the ground. On the other hand, by rotating the hand wheel 44 in the opposite direction, the inner ends of the blades may be lowered for caus- 90

ing the inner end portions of the blades to bite into the ground. It will accordingly be seen that I provide a grader wherein the scraper blades may be elevated or lowered, 5 may be adjustably rocked or their inclination reversed horizontally, and may also be tilted longitudinally. Adequate control of the blades is thus had so that the grader will accordingly prove correspondingly effective in use. Furthermore, it is to be observed that any one adjustment of the blades may be made without changing any of the other adjustments thereof.

Having thus described the invention, what 15 is claimed as new is:

1. A grading machine including a frame, companion blades freely connected therewith, a rock beam carried by the frame, means connecting corresponding end portions of the blades with said beam, and means for rocking said beam whereby to tilt the blades longitudinally.

2. A grading machine including a frame, companion blades freely connected therewith, a pivoted beam, means connecting corresponding end portions of the blades with said beam, and means coacting with one end portion of the beam for swinging said beam whereby to tilt the blades longitudinally.

3. A grading machine including a frame, companion blades freely connected therewith, a pivoted beam, means carried by the beam and coupled with corresponding end portions of the blades for swinging the blades horizontally, and means coacting with one end portion of the beam for pivoting the beam whereby to tilt the blades longitudinally.

4. A grading machine including a frame, 40 companion blades freely connected therewith, a pivoted beam, a carrier shiftable upon the beam, means coupling the carrier with corresponding end portions of the blades, means for shifting the carrier upon the beam whereby to swing the blades horizontally, and means coacting with one end portion of the beam for pivoting the beam whereby to tilt the blades longitudinally.

5. A grading machine including a frame, 50 arms pivoted upon the frame, companion blades freely connected intermediate their ends to said arms, a loose connection be-

tween the inner adjacent ends of the blades, an elevating bar, means coupling the bar with said blades intermediate the ends of 55 the blades, and means for shifting the bar vertically to elevate or lower the blades.

6. A grading machine including a frame, arms freely connected therewith, companion blades freely mounted intermediate their 60 ends upon said arms, a loose connection between the inner adjacent ends of the blades, posts rising from the frame at opposite sides of the center thereof, an elevating bar 65 slideable vertically upon said posts, coupling means between the bar and the blades, and means for adjustably positioning the bar vertically upon the posts whereby to raise or lower the blades.

7. A grading machine including a frame, 70 arms pivotally connected with the frame, companion blades freely mounted intermediate their ends upon said arms, means coupled with the blades for raising or lowering the blades, a carrier on the frame, means for loosely connecting the inner adjacent 75 ends of the blades with each other and with the carrier, and means for shifting the carrier longitudinally of the frame whereby to rotate the blades upon the arms and vary 80 the angular relation of the blades.

8. A grading machine including a frame, arms pivotally connected with the frame, companion blades freely mounted upon said arms, means coupled with the blades for 85 elevating or lowering the blades, means for rotating the blades upon the arms to position the blades in angular relation to each other, and means connected to corresponding end portions of the blades for rocking the 90 blades upon the arms and tilting the blades longitudinally.

9. A grading machine including a frame, arms freely connected therewith, companion blades carried by said arms, and means 95 connected with corresponding ends of the blades for swinging the blades horizontally and movable to position the blades inclining inwardly toward each other or position the blades inclining outwardly away from 100 each other.

In testimony whereof I affix my signature.

CARL P. MILLER. [L.S.]
